Primary Examiner — Susan Bennett Hattan*Assistant Examiner* — Leanne Was(74) *Attorney, Agent, or Firm* — Hodgson Russ LLP**CLAIM**

The ornamental design for a lid bottom, as shown and described.

DESCRIPTION

FIG. 1 is a front perspective view of a lid bottom showing my new design;

FIG. 2 is a front view thereof;

FIG. 3 is a right side view thereof;

FIG. 4 is a rear view thereof;

FIG. 5 is a top view thereof;

FIG. 6 is a bottom view thereof;

FIG. 7 is a front perspective view with the plunger of the lid bottom removed for ease of illustration; and,

FIG. 8 is a bottom view the plunger of the lid bottom removed for ease of illustration.

The broken lines illustrate portions of the lid bottom and form no part of the claimed design.
